UNITED STATES PATENT OFFICE.

JACOB GEIGER AND PHILIP E. BUSH, OF BUCYRUS, OHIO.

WIRING-MACHINE.

SPECIFICATION forming part of Letters Patent No. 245,154, dated August 2, 1881.

Application filed July 12, 1881. (Model.)

To all whom it may concern:

Be it known that we, JACOB GEIGER and PHILIP E. BUSH, of Bucyrus, county of Crawford, and State of Ohio, have invented a new and useful Improvement in Wiring-Machines, of which the following is a clear, full, and exact description, reference being had to the accompanying drawings, making a part of this specification, in which—

10 Figure 1 is a perspective view of a wiring-machine with our improvements attached. Fig. 2 is a front elevation of the same.

To enable others skilled in the art to make and use our invention, we will proceed to describe the exact manner in which we have carried it out.

Our invention has special reference to wiring the rims of large copper and brass kettles; and it consists of the combination of devices 20 as hereinafter described and claimed.

In the drawings, A is the frame for supporting the ordinary machinery of wiring-machines.

The gearing for giving motion to the formers or revolving heads is all of well-known construction.

25 On a lower shaft, B, is fixed an elongated grooved hub or former, C, and on an upper shaft, F, arranged in a line with shaft B, is a short hub or former, D, which projects into the mouth of the kettle or can being wired, and is provided with a groove corresponding to the groove in hub C. The peculiar conformation of the lower former prevents the crimping of the portion of the sheet metal within a short 35 distance of the rim by sustaining it and preventing the base of the can from dropping down, the inner surface being retained in a uniform shape, and the metal is made to fit closely to the wire. The flange d on the outer edge of 40 hub D forces the edge of the metal tightly around the wire and down against the body of the kettle.

To sustain the end of shaft B we provide a removable standard, S, which has a bearing for 45 said shaft in its upper end and slides into a slot, t, in the base of the machine. This construction renders the hub C readily removable.

In wiring-machines now in use by tinnings and others gaps are left under the wire, or the 50 rim is closed against the body of the kettle with a straight edge below the wire, while by our improvement the metal takes the shape of the wire and has a smooth surface. It also is

evident from our construction that the wired rim of the kettle will be set partially over the 55 inner surface of the kettle. The wired rim being thus set, the wire is more securely held in position than if the extension was altogether outward, and the inner edge of the kettle is less liable to receive bruises, while the inner 60 extension of the rim furnishes a stop to boiling fluids, and thus lessens the liability to overflow.

We provide the guide E with a facing of 65 wood or leather, the latter being found preferable. The friction of the kettle against a metal guide has the effect to deposit copper on the face of the guide, which by degrees hardens it beyond the hardness of ordinary copper, so that the rim of the kettle is liable to become 70 scratched and defaced. To overcome this difficulty we face the metal guide with leather or other suitable soft material, as shown in Fig. 1.

In operating our device the rim of the kettle is first upset in the usual way, so as to have 75 the metal turned back upon itself, but leaving room for insertion of the wire. The open end of the kettle is then placed over the elongated head of the lower former and pressed up against the guide E, the upper former, D, having previously been raised by the adjusting mechanism G. The wire is then inserted under the upset rim and the former D lowered, so as to 80 press the metal around the wire, as will be obvious. The formers are then rotated by any 85 suitable means until the entire rim has been wired, when the former D is again raised, as before.

Having thus described our invention, what 90 we claim as new, and desire to secure by Letters Patent, is—

1. In a wiring-machine, the elongated grooved former C, in combination with the grooved former D, provided with the sharp flange d, substantially as and for the purpose set forth. 95

2. In a wiring-machine, the elongated grooved former C and the grooved former D, provided with the sharp flange d, in combination with the guide E, provided with a face of suitable soft material, substantially as described.

JACOB GEIGER.
PHILIP E. BUSH.
